UNITED STATES PATENT OFFICE

2,448,056

CUTTINGS CONVEYING MEANS

Leon E. Simmons, Claremont, N. H., assignor to
 Joy Manufacturing Company, a corporation of
 Pennsylvania

Application August 11, 1943; Serial No. 498,194

2 Claims. (Cl. 262—30)

1

This invention relates to cuttings conveying means and more particularly, but not exclusively, to improvements in a cuttings conveying means for a coal cutting machine of the flexibly fed, room and pillar, floor cutter type.

In the cutting of coal by the use of modern high speed coal cutting machines of the room and pillar, endless cutter chain type, the cuttings created by the cutters of the cutter chain during the kerf cutting operation accumulate so rapidly at the rear end of the cutter bar that it is practically impossible, by most present day methods, to remove them sufficiently rapidly, and, as a result, a large quantity of cuttings piles up around the rear end of the machine in such manner as materially to reduce the cutting efficiency. It has been common practice manually to shovel the cuttings away from the machine, employing two or more shovelers, a laborious task, with many attendant dangers, and, even then, a large amount of the cuttings are conveyed back into the kerf, resulting in increased power consumption and wear of the cutter parts, and loss of efficiency. Known attempts have been made to remove mechanically the cuttings from the vicinity of the cutter chain of a room and pillar coal cutting machine, but such known mechanisms are relatively bulky, greatly increase the longitudinal dimensions of the machine, preventing close setting of roof props, and, due to their design, are relatively noisy in operation and create considerable hazardous dust. It is also known that a single spiral conveyor has been employed in longwall coal cutting machines of comparatively small capacity to convey away the cuttings, but it has been found that in high capacity room and pillar coal cutting machines a single spiral conveyor of sufficient capacity to accommodate the large amount of cuttings would necessarily be of extremely large dimensions, and, as a result, it was found impossible to locate such a relatively large conveyor sufficiently close to the cutter chain of the machine to enable efficient operation without substantially modifying the coal cutting machine. A spiral type conveyor was found, however, to have many advantages in that it is extremely compact, permitting relatively close setting of the roof props, operates in a quiet and efficient manner and creates little hazardous dust.

An object of the present invention is to provide a cuttings conveyor means especially designed for use in a modern high speed room and pillar type coal cutting machine, and one which overcomes the disadvantages of conveying means

2

of known types. Another object is to provide an improved cuttings conveying means having relatively great efficiency while desirable compactness is obtained, and the creation of objectionable dust is minimized. A further object is to provide an improved cuttings conveying means of the spiral conveyor type wherein, while obtaining relatively large capacity, it is possible to locate the conveying means relatively close to the cutter chain of the coal cutting machine. Yet another object is to provide a cuttings conveying means embodying two or more coacting conveying devices which serve to move large quantities of cuttings from the vicinity of the cutter chain. A still further object is to provide an improved cuttings conveying means embodying two or more coacting spiral conveyors arranged in a novel manner. Still another object is to provide two or more spiral conveyors arranged in an improved manner on spaced apart parallel axes extending longitudinally of the coal cutting machine. A further object is to provide an improved cuttings conveying means having novel driving means and novel means for mounting the same on and attaching the same to a coal cutting machine. Another object is to provide an improved cuttings conveying means which is arranged within the projection of the lateral limits of the machine and which projects only a comparatively short distance from the rear end of the machine. A further object is to provide an improved reversible cuttings conveying means adapted to use with a reversible type coal cutting machine for conveying away the cuttings from the machine irrespective of the direction in which the machine is operated. Still another object is to provide an improved reversible cuttings conveying means of the multiple spiral conveyor type embodying interchangeable spiral conveyors whereby operation in either of opposite directions is possible by a simple interchange of parts. Other objects and advantages of the invention will be clearly apparent to those skilled in the art.

45 In the accompanying drawings there are shown for purposes of illustration two forms which the invention may assume in practice.

In these drawings:

Fig. 1 is a plan view of a coal cutting machine equipped with an illustrative form of the improved cuttings conveying means.

Fig. 2 is a side elevational view of the cutting machine and conveying means shown in Fig. 1.

Fig. 3 is an enlarged rear end elevational view of the cutting machine and conveying means

55

shown in Figs. 1 and 2, with a portion of the machine broken away to facilitate illustration.

Fig. 4 is an enlarged cross sectional view taken substantially on line 4—4 of Fig. 1, illustrating a portion of the conveyor drive.

Fig. 5 is an enlarged view in longitudinal vertical section taken substantially on line 5—5 of Fig. 1.

Fig. 6 is an enlarged horizontal sectional view taken substantially on line 6—6 of Fig. 3.

Fig. 7 is an enlarged cross sectional view taken substantially on line 7—7 of Fig. 1.

Fig. 8 is a cross sectional view taken substantially on line 8—8 of Fig. 6.

Fig. 9 is a detail vertical sectional view taken substantially on line 9—9 of Fig. 6.

Fig. 10 is a fragmentary plan view of a coal cutting machine equipped with a cuttings conveying means of a modified construction.

Fig. 11 is a fragmentary side elevational view of the cutting machine and conveying means shown in Fig. 10.

Fig. 12 is an enlarged cross sectional view taken substantially on line 12—12 of Fig. 10, showing a portion of the conveyor drive.

Fig. 13 is an enlarged view in longitudinal vertical section taken substantially on line 13—13 of Fig. 10.

Fig. 14 is an enlarged rear end elevational view of the cutting machine and conveying means shown in Figs. 10 and 11, with a portion of the machine broken away.

Fig. 15 is an enlarged cross sectional view taken substantially on line 15—15 of Fig. 11.

Fig. 16 is an enlarged horizontal sectional view taken substantially on line 16—16 of Fig. 14.

In both illustrative embodiments of the invention the improved cuttings conveying means is associated with a coal cutting machine of the flexibly fed, room and pillar, floor cutter type. The coal cutting machine shown is of a conventional design and may be similar to that disclosed in Patent No. 2,131,178, patented September 27, 1938, in which I am one of the joint inventors. It will be evident, of course, that the improved conveying means may be associated with coal cutting machines of other types.

The coal cutting machine, as disclosed herein, comprises a machine frame 1 mounted on a bottom plate or shoe 2 slideable on the floor of a mine. Extending longitudinally throughout the length of the lower portion of the machine frame is a chamber 3 having projecting therein and secured to the machine frame the rearward portion of an elongated horizontal plane cutter bar 4, the latter having mounted on its margin for circulation thereabout an endless cutter chain 5. The flexible feeding means may comprise feeding and controlling drums 6 and 7 respectively having wound thereon feeding and controlling cables 8 and 9. Carried by the machine frame is a motor 10 having its power shaft operatively connected to the cutter chain and the feeding and controlling drums for effecting drive thereof. As shown in Fig. 14 of the patent above referred to, the motor power shaft is connected through spur and bevel gears to a vertical shaft 11 (Fig. 6) to which is keyed a chain sprocket 12 arranged in the chamber 3 and engaging and driving the endless cutter chain 5. As shown in Figs. 13 and 14 of the patent above referred to, the motor power shaft is operatively connected through separate high and low speed gearings to the feeding and controlling drums 6 and 7 to effect independent driving of the latter at either high or low cable

winding speeds. In Fig. 5 herein a portion of the high and low speed gearings for one of the drums is shown. A high speed gear 13 is connectible by a multiple disk clutch 14 to a horizontal shaft 15 which extends longitudinally of the machine and is suitably journaled in the machine frame. Driven by this shaft is a worm 16 meshing with a worm wheel 17 which is connectible by a multiple disk clutch 18 to a horizontal transversely extending shaft 19, the latter being operatively connected to one of the cable winding drums, herein the drum 7. A low speed gear 20 is connectible by a multiple disk clutch 21 to the shaft 15. The clutches 14 and 21 have suitable operating means so that when one is applied the other is released.

The feeding and controlling cables 8 and 9 may be extended from the feeding and controlling drums 6 and 7 around appropriately located guide sheaves on the machine in a conventional manner and are connectible at their free ends to suitable anchor jacks located at the rib and face of the room of a mine. The cutter chain when connected in driven relation with the motor may be rapidly circulated about the margin of the cutter bar, and, as the cables are wound in by the motor driven drums, the cutter bar may be sumped beneath the coal at one rib, thereafter be fed transversely across the coal face to cut a horizontal kerf beneath the coal, and finally be withdrawn from the face at the opposite rib. The feeding drum effects feed of the machine and the controlling drum controls the angle of the machine with respect to the coal face during the kerf cutting operations all in the manners well known to those skilled in the art. During the kerf cutting operation, the cuttings created by the cutters of the cutter chain are carried back from the kerf through the chamber 3 extending through the lower portion of the machine for discharge at the rear end of the machine. Since the mode of operation of a room and pillar coal cutting machine of the type disclosed is well known and is fully described in the patent above referred to, further description thereof is herein unnecessary.

In the embodiment of the invention shown in Figs. 1 to 9 inclusive, the improved cuttings conveying means generally designated 25, is attached to the rear end of the coal cutting machine and is arranged in such manner that its conveying elements remove the cuttings from the vicinity of the cutter chain at the rear end of the chamber 3 and convey the cuttings to discharge rearwardly of the machine out of the machine path. Now referring to the specific structure of the improved cuttings conveying means, it will be noted that arranged in a casing 26 are coacting conveyor devices, herein preferably three spiral conveyors 27, 28 and 29 arranged in parallel offset relation on horizontal axes extending longitudinally of the coal cutting machine. The conveyor casing has parallel horizontal bores 30 for receiving portions of the spiral conveyors (Fig. 7) and as shown in Fig. 8, these bores each communicate at their forward ends with a transverse chamber 31 which forms a continuation of the frame-chamber 3. As illustrated, the conveyor casing 26 has lip portions or feet 32 (Fig. 9) overlying and resting on the bottom skid plate of the machine, and the conveyor casing is suitably fitted to the rear end of the machine in an extremely compact manner. The conveyor casing includes a main portion or section 33 which carries the lip portions or feet 32 and a detachable rearward upper housing portion 34, the two parts

of the casing having a horizontal junction as at 35. The bottom portion 33 of the conveyor casing is rigidly attached as by screws 36 to the frame of the coal cutting machine while the upper housing 34 is readily detachable. For releasably attaching the upper housing 34 to the bottom portion 33 of the conveyor casing, there are provided eyebolts 37 (Figs. 6 and 7) pivotally mounted at 38 on the bottom casing section 33 and swingable laterally into vertical slots 39 formed on lateral projections integral with the upper housing 34. Threaded on the upper ends of the eyebolts are suitable wing nuts 40 which, when tightened, firmly clamp the upper housing to the bottom casing section. By loosening these wing nuts and swinging the eyebolts laterally from the slots 39, the upper housing may be readily detached. The three spiral conveyors 27, 28 and 29 project forwardly into the machine frame and are arranged with respect to the path of the cutter chain 5 in the manner shown in Fig. 6, and, as the cutter chain moves the cuttings rearwardly in the chamber 3, the spiral conveyors receive the cuttings and convey the cuttings rearwardly through the bores 30 in the conveyor casing to discharge at the rear end of the machine out of the machine path. These spiral conveyors preferably all rotate in the same direction and are driven by the motor 10 of the coal cutting machine. The two outer conveyors are somewhat longer than the central conveyor, in the manner shown.

The conveyor driving means may assume various forms and herein comprises a shaft 41 (Fig. 5) extending centrally longitudinally through a bore in the shaft 15 and keyed at its forward end to a shaft 42 in turn keyed to the hub of the gear 13 and driven by the latter. The shaft 41 is clutched at 43 at its rear end to the hub of a cone 44 of a frictional cone clutch. The cone 44 is held by a spring 45 in frictional engagement with the walls of a conical bore 46 formed in a clutch member 47. This clutch member has its hub keyed to a horizontal longitudinally extending shaft 48 herein arranged in a tubular housing 49 suitably detachably secured at its inner end to the rear end of the machine frame. Secured to and driven by the shaft 48 is a spur gear 50 arranged in a gear housing 51 preferably detachably secured to the bottom section 33 of the conveyor casing. As is also shown in Fig. 5, the gear 50 meshes with a gear 52 which in turn meshes with a gear 53. The gear 53 meshes with and drives a gear 54 which meshes with a gear 55, the latter in turn meshing with and driving a gear 56 which meshes with and drives a gear 57. Meshing with and driven by the gears 53, 55 and 57 respectively, are gears 58, 59 and 60. As shown in Fig. 6, the gears 58, 59 and 60 are secured to horizontal longitudinally extending shafts 61, 62 and 63 respectively, suitably journaled in the housing of the conveyor casing and to which the spiral conveyors 27, 28 and 29 are respectively secured. An open space 64 is arranged beneath the gear housings of the conveyor casing as shown in Figs. 3 and 4 so that the cuttings conveyed rearwardly by the spiral conveyors may be discharged freely from the rear end of the conveyor casing. Upon removal of the screws 36 and detachment of the tubular housings 49 from the machine frame, the cuttings conveying means may be removed rearwardly as a unit from the rear end of the coal cutting machine, the connection between the conveyors and the machine

gearing releasing at the clutch 43, as the conveying means is moved rearwardly.

In Figs. 10 to 16 inclusive, a modified form of the cuttings conveying means is shown. This cuttings conveying means is generally designated 65 and may comprise a casing 66 attached to the rear end of the coal cutting machine. Arranged in horizontal bores 67 in this casing is a pair of coacting spiral conveyors 68 and 69. These conveyors project inwardly into the machine frame and extend into a chamber 70 which forms a continuation of the frame chamber 3 with their forward ends in adjacency to the path of travel of the cutter chain 5, and are the conveyors preferably arranged on spaced apart parallel horizontal axes extending longitudinally of the machine. The conveyor casing 66 includes a bottom casing section 71 rigidly attached by screws 72 to the machine frame and detachable upper housings 73 secured by eyebolts 74 to the bottom casing section. These upper housings may be readily removed to obtain access to the conveyors. In this construction, the conveyors are separately driven through the individual driving gearings for the feeding and controlling drums 6 and 7. As shown in Fig. 13, each conveyor is driven through a releasable clutch 75 similar to the clutch 43 and connected through frictional cone clutches 76 to parallel longitudinally extending shafts 77. These shafts extend through tubular housings 78 suitably attached to the machine frame, and have secured to their rear ends gears 79 (see also Fig. 12). The gears 79 mesh with and drive gears 80 which in turn mesh with and drive gears 81 fixed to parallel longitudinally extending shafts 82. The gears 79, 80 and 81 are enclosed within housings 83 on the detachable upper portions 73 of the conveyor casing, and the shafts 82 are suitably journaled at their rear ends within these housings. The spiral conveyors 68 and 69 are fixed to and driven by the shafts 82. Thus the spiral conveyors may be driven through the driving gearings for the cable winding drums of the coal cutting machine in relatively opposite directions.

As described in the patent above referred to, the coal cutting machine may operate in either of opposite directions to cut horizontal kerfs in the coal, and, in this instance, the cuttings conveying means is made reversible so as to convey away the cuttings from the vicinity of the cutter chain irrespective to the direction in which the machine is operating. To enable reversal of the cuttings conveying means the spiral conveyors 68 and 69 are made interchangeable and such interchange of the conveyors is made possible simply by removing the detachable upper housings and interchanging one conveyor for the other. Such interchange of the spiral conveyors enables operation of the conveyors in the proper direction irrespective of the direction in which the coal cutting machine is operating. Extending longitudinally of the conveyor casing intermediate the spiral conveyors is a chamber 84 through which some of the cuttings carried back by the cutter chain may be discharged from the machine, and arranged beneath the gear housings 83 are spaces 85 through which the cuttings conveyed rearwardly by the spiral conveyors may be discharged from the machine. The conveying means may be detached from the machine as a unit simply by removing the screws which fasten the same to the machine frame and moving the conveying means bodily in a rearward direction, the drive connections between the conveyors and the machine gearing releasing

automatically as the conveying means is so moved. The conveyors may be readily removed from the casing while the bottom casing section remains fixed to the machine frame simply by removing the upper gear housings. Such ready detachment of the conveyors facilitates the interchangeability thereof for reverse cutting.

In both embodiments of the improved conveying means, the frictional cone clutches in the conveyor drives are set at a predetermined load to slip automatically in the event the conveyors become overloaded, thereby to prevent damage to the parts. Evidently, the conveying means of the triple spiral conveyor form may have the conveyors replaced with conveyors having spirals of opposite lead to enable reverse operation during cutting in a reverse direction.

As a result of this invention an improved cuttings conveying means is provided which overcomes the disadvantages of known types of cuttings conveyors. It will further be noted that by the provision of two or more coacting conveyor devices, large quantities of cuttings may be conveyed from the vicinity of the cutter chain of a modern high speed coal cutting machine. It will further be evident that by the provision of two or more conveyor devices arranged in the manner disclosed, large quantities of cuttings may be conveyed from the coal cutting machine, resulting in more efficient operation. The spiral conveyors are relatively quiet in operation, create comparatively little hazardous dust, and are extremely compact, enabling relatively close setting of roof props. By the provision of the interchangeable spiral conveyors, the conveying means may be readily reversed so that the cuttings may be conveyed from the coal cutting machine irrespective of the direction of operation thereof. Other advantages of the invention will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A cuttings conveying means adapted for association with a coal cutting machine having a frame carrying kerf cutting devices, comprising a conveyor casing having a chamber adapted to receive cuttings from the machine and having spaced apart parallel openings extending longitudinally of the machine frame when in use, the adjacent walls of said openings arranged in spaced apart relation to provide a longitudinal space between said walls, coacting relatively movable conveyor devices operating to move the cuttings from the vicinity of the cutting devices, said conveyor devices arranged longitudinally in said openings respectively and having their inner cuttings-receiving-ends in adjacency to the kerf cutting devices and their outer discharge-ends remote from the kerf cutting devices, said conveyor devices

5 having portions thereof completely enclosed by the opening-walls and other longitudinally inwardly spaced portions disposed in free transverse communication with said space nearer the side toward the kerf cutting devices, and means for concurrently driving said conveyor devices, said conveyor devices arranged and constructed to receive the cuttings at the inner ends of said openings and to move the cuttings longitudinally through said openings to discharge at the outer side of said casing, and said space between said adjacent opening-walls providing a longitudinal passageway between said conveyor devices for the discharge of a portion of the cuttings longitudinally away from the kerf cutting devices.

10 2. A cuttings conveying means adapted for association with a coal cutting machine of the kind having orbitally moving kerf cutting devices guided for circulation in a cuttings-receiving chamber 20 within the frame of the machine, comprising a casing attachable to the machine frame and having a chamber adapted to communicate with the machine-frame chamber to receive the cuttings discharged from said frame chamber, said casing 25 having spaced apart parallel bores extending when in use longitudinally of the machine frame with one bore at each side of the longitudinal vertical center of the machine frame and casing, the inner adjacent walls of said bores being arranged in spaced apart relation to provide a longitudinal space between said walls, rotatable spiral conveyors arranged in said bores respectively and operating to move the cuttings from the vicinity 30 of the cutter chain through said bores and to discharge the cuttings outwardly from said casing, said conveyors operating in a longitudinal direction relative to the machine frame and having cuttings-receiving portions projecting longitudinally inwardly from said bores into the machine frame into adjacency to the cutting devices, and means for concurrently rotating said conveyors, said space between said adjacent bore-walls providing a longitudinal passageway between said 35 conveyors for the discharge of a portion of the cuttings outwardly from the casing chamber independently of said conveyors.
